BUCKSHOT SHELLS FOR SHOTGUNS
Gerald V. Schaefer, 658 S. Edge Park Drive, Haddonfield,
N.J., assignor of one-half to John B. Kelly, Borough
of Haddonfield, Camden County, N.J.
Filed Apr. 4, 1963, Ser. No. 270,603
8 Claims. (Cl. 102—42)

This invention relates to buckshot shells for shotguns and to means carried by the shells for improving the functioning of the buckshot and of the shotguns, loaded with the shells, when fired. The present application is a continuation-in-part of application Serial No. 230,811, filed October 16, 1962 for Buckshot Shells for Shotguns.

An important object of the invention is to provide buckshot shells for shotguns which shells contain means for improving the buckshot patterns. For example, patterns with an average spread of 15 inches can be expected at 40 yards, with other spreads in proportion.

Another important object of the invention is to provide buckshot shells for shotguns which shells contain the means as above, which also function to increase velocity by aligning the buckshot in such manner that the friction between the buckshot and the shell case and the friction between the buckshot and the gun barrel are reduced.

Still another important object of the invention is to provide buckshot shells for shotguns which shells contain the means referred to above which also aids in effective penetration of the buckshot because the spherical shot is less distorted during its passage through the shotgun barrel than is the case when using conventional shotgun shells.

In addition an important object of the invention is to provide buckshot shells containing means as above which, for a given velocity, lower the breech pressure in the shotgun during propellant combustion.

Still another important object is to provide shotgun shells as above, the use of which will cause less recoil of the shotgun for a given velocity.

I am aware of shells containing small granules of various substances mixed with or in which relatively fine shot is imbedded, but not in any regular pattern, as well as shells in which the shot is adhesively held together, or in which projectiles of cylindrical shape are separated so that, when fired they are said to take spiral paths within a gun barrel and not fuse together, but these are not the shells of my invention, since the shells I provide are preferably adapted to contain buckshot of substantially spherical shape and of a relatively large size, such as the shot commonly known as No. 0 buck, of about .30 caliber (although larger caliber shot may be used) and the individual shot separated one from another in a regular pattern transversely and longitudinally of the shell casing with a layer, as two of the shot, in substantially the same horizontal plane (when the shell is upended) but not in the same vertical planes as those of the two shot in the next adjacent layer.

An additional important object is to provide articles of manufacture which are termed herein as patterned bodies for insertion in the buckshot shell casings in order to provide the means referred to heretofore in this specification. Such patterned bodies may have substantially smooth peripheral surfaces or may have an indented, fluted or serrated peripheral surface, since I have discovered that the provision of flutes or serrations provide an unexpected and very desirable result.

Other objects and advantages of this invention will be apparent during the course of the following detailed description, taken in connection with the accompanying drawing, forming a part of this specification, and in which drawing:

FIG. 1 is a fragmentary longitudinal sectional view of a shell of this invention.

2

FIG. 2 is a horizontal sectional view (somewhat enlarged) substantially on the line 2—2 of FIG. 1.

FIG. 3 is a perspective view of the patterned body disclosed in detail in this present application.

5 FIG. 4 is a fragmentary longitudinal sectional view of a shotgun barrel, with buckshot, patterned bodies and wads in position as being propelled therethrough.

In the drawing, wherein for the purpose of illustration is shown a typical embodiment of the invention and wherein similar reference characters designate corresponding parts throughout the several views, the letter A designates a buckshot shell for shotguns containing a form of the patterned body B of this present application, and C designates a shotgun.

10 15 FIG. 4 is a fragmentary longitudinal sectional view of a shotgun barrel, with buckshot, patterned bodies and wads in position as being propelled therethrough.

20 The buckshot shell for shotguns, designated as A, includes a casing 10, having a substantially cylindrical tubular side wall 11 with the outer end portion thereof preferably folded inwardly in order to provide a closure 12 as is well known in the art. The casing may be of

25 waxed paper, cardboard or the like.

The shell A may also include a conventional rear end cap and a conventional detonating means and, communicating with the detonating means, is a supply of suitable propellant, as powder, filling a portion of the casing 10 and conventionally retained by wadding, such as the wadding 16 and 17 of FIG. 4 and also all of this construction is disclosed in my co-pending application referred to above.

30 Buckshot 18 for use is preferably that commonly known as "No. 0 buck" of about .30 caliber. Larger buckshot may be used. The buckshot is substantially spherical, and is disposed in regular patterns within the casing 10, as may be appreciated from FIGS. 1 and 2. That is, for example, two of the buckshot 18 are arranged with their centers substantially 180° apart within the casing and at the same level or horizontal plane (considering the shell A as upstanding upon its end cap) with the two buckshot 18 of the next level also substantially 180° apart, both being in the same horizontal plane, but in vertical planes with their vertical axes spaced 90° from the vertical axes of the first mentioned two buckshot 18. This pattern of spacing of the buckshot may be repeated, from the closure 12 to adjacent the wad 17, throughout the casing 10.

35 40 45 The buckshot 18 are retained in the positions described above by the patterned bodies B.

While the patterned bodies B illustrated in FIGS. 1 to 4 inclusive of this present application are substantially similar to one of the patterned bodies (the patterned body C) of my co-pending application referred to above, except for the flutes, serrations or indentations, it should be understood that the general shape of the patterned bodies A of the present invention is given by way of example and they may have the general shapes of the other patterned bodies, also given by way of example, in my co-pending application referred to above, with the additions of the indentations, flutes or serrations.

50 55 Now as to the patterned body B of the present application, the same includes a shell side wall-contacting arcuate face 20 adapted to engage a portion of the inner face of the side wall 11. From each lateral edge 21 of the face 20 extends a buckshot-contacting face 22, with the two faces 22 converging so as to join one another as at the juncture 23 which may be an edge of somewhat less height than the width of the face 20. Defined by the edges 24 of the face 20 and the edges 25 of the faces 22 are buckshot-receiving concavities 26. Thus, each patterned body B has two of these concavities 26. By way of example, the length of the arcuate face 20 may be substantially $\frac{1}{16}$ inch, its width substantially $\frac{1}{4}$ inch, the edges 25 each $\frac{1}{16}$ inch, the edge 23 substantially

70

$\frac{3}{16}$ inch. The size and depth of the concavities 26 are such as to receive a portion of the buckshot, substantially as may be seen in FIG. 1.

I have discovered that the provision of indentations, particularly flutes or serrations, extending substantially transversely of the arcuate face 20 with their mouths opening to that face, act as anti-friction means during passage of the patterned bodies B through the shotgun barrel. Preferably the indentations, flutes or serrations (which will be referred to simply as indentations 28, hereinafter) extend from one edge 24 to the opposite edge 24 of the face 20 as may be seen in FIG. 3, thus reducing the area of the face 20 materially. For example, there may be eight substantially parallel indentations per quarter inch of length of a face 20, substantially three-quarter inch in length. The depth of the indentations may be, by way of example, one thirty-second inch. Of course, depending upon the area of the face 20, these measurements may vary. The important element is that the longitudinal axes of the indentations substantially parallel the longitudinal axis of the shell containing the patterned bodies B and, consequently, parallel as well the longitudinal axis of a shotgun barrel through which they pass when the shell is fired therein.

The patterned body B may be made of any suitable material which has some degree of resiliency for cushioning the buckshot, is readily moulded or stamped to shape, is inexpensive and not apt to disintegrate upon firing of the shell in which it is encased. Such materials may be shell wadding felt, compacted and held together with any suitable adhesive such as glue. They may also be constructed of stout cardboard, resins such as polyethylene, or nylon.

After the wadding is in place within the open-ended shell casing 10, two of the patterned bodies are placed, with their junctures 23 facing and their faces 20 in contact with the inner face of the casing side wall 11. Two buckshot 18 are then disposed so as to lie between opposite faces 22 of the two patterned bodies in a somewhat wedged relation therewith and disposed substantially 180° apart. Two more of the patterned bodies, with their face junctures 23 facing one another are then positioned with the concavities enclosing the upper portions of the two buckshot, then two more of the buckshot are disposed in the wedged relation, and so on until the shell is fully loaded, whereupon the closure 12 is folded over the outermost two buckshot. It should be borne in mind that there is no need to ascertain which concave face of the patterned body is uppermost or lowermost since both of these particular faces are alike. This permits a faster loading of the shell.

FIG. 4 illustrates how the patterned bodies and buckshot (together with the wads) pass through the barrel 40 of the shot gun C. It will be seen that, while the arcuate faces, such as the faces 20 of the patterned bodies B, may have some limited sliding contact with the inner surface 41 of the gun barrel, the buckshot are cradled on and disposed between the patterned bodies. Neither are they scattered during passage through the barrel nor impinge on one another and become fused together or deform one another. Although some sliding contact may occur between buckshot and the gun barrel, especially when going through the choke 42, no undue lateral force is exerted. Obviously, the buckshot remains in its initially disposed place during the life of the unfired shell, since the patterned bodies, unlike fine or coarse materials in which shot is imbedded, do not move about while in the shells. The buckshot and patterned bodies, being in a compact mass as they travel through the gunbarrel do not permit the buckshot to spin during such travel. Spinning tends to cause shot to yaw or its path to assume a curve.

What has been said about the spacing of the buckshot 18 from each other while in the shotgun barrel is characteristic of the buckshot within the casing 10 and spaced from each other in a positively spaced-apart pattern.

While there is illustrated two buckshot per layer, this number may be increased. The inside diameter of a 12-gauge barrel, for instance, at the end of the choke portion, is approximately .720 inch. If two buckshot per layer are used each buckshot would be approximately .360 inch. If three buckshot per layer are used the three buckshot would be of such a diameter that they would fit snugly in a .720 inch circle.

As described previously, with the exception of the first two inserted buckshot, a patterned body is disposed under each buckshot. The buckshot of each succeeding layer rest on the patterned body of the preceding layer, the result being that buckshot never rest on buckshot but always rest on or between patterned bodies. Each buckshot, except the first two inserted buckshot, is cradled as on a cushion and all are disposed between patterned bodies. Each cradled buckshot is lifted as by a cushion and in turn lifts the patterned body ahead, each buckshot is thus held in a parallel course in its flight along the gun barrel and tends to hold this parallel course in flight after leaving the muzzle, giving smaller and more compact patterns than are obtained without the use of the patterned bodies.

Not only do the indentations 28 reduce friction but they provide ideal recesses for lubricants, such as graphite or heavy greases, which can be very readily spread thereinto and function as is well known in the art.

It will be noted, that the width of the wall 20 is greater than the width of either face 22, so that the buckshot have a tendency, due to this, to move slightly toward each other (but not contact each other) whereby they do not tend to forcibly contact and push outwardly the side wall of the shell as one after another buckshot is inserted in the shell while loading since the weight of the large buckshot in the loaded shell is considerable, as is obvious.

Considering the size of the buckshot and the patterned bodies, the shells may be readily and correctly loaded by hand with the buckshot and patterned bodies.

What is claimed is:

1. Buckshot shell for shotguns, said shell including a casing, buckshot propellant and a plurality of buckshot within the casing, means within said casing for positively separating each of said buckshot, one from another; and wadding between said propellant and said means, said means comprising a plurality of patterned bodies, one for each buckshot, each of the same shape and having a face contacting the wall of said casing and for contacting the inner periphery of a shotgun barrel, said bodies being provided with a plurality of spaced part indentations opening to said face, whereby the area of said face is reduced and there are provided recesses defined by said indentations to receive lubricant facing said casing.

2. Buckshot shell according to claim 1 characterized in that said indentations and the portions of said face between the mouths of said indentations extend with their longitudinal axis substantially paralleling the longitudinal axis of said casing.

3. Buckshot shell according to claim 2 characterized in that each of said patterned bodies has two opposite faces for receiving buckshot thereon and the junctures of said opposite faces and said face provide longitudinal edges, and said indentations extend to said edges with the end mouths of said indentations opening at said two opposite faces.

4. Buckshot shell according to claim 2 characterized in that each of said patterned bodies has two opposite faces for receiving buckshot thereon and the junctures of said opposite faces and said face provide longitudinal edges, and said indentations have substantially parallel longitudinal sides and extend to said edges with the end mouths of said indentations opening at said two opposite faces.

5. As an article of manufacture a patterned body for separating substantially spherical buckshot, one from another in a shotgun shell, said body having an arcuate cas-

ing wall-contacting face, a pair of buckshot contacting faces, converging together from the ends of said arcuate face, and a buckshot receiving concavity with its mouth defined by edges of said arcuate face and a pair of faces, and said body being provided with a plurality of spaced-apart indentations extending inwardly from said arcuate casing wall-contacting face.

6. As an article of manufacture a patterned body for separating substantially spherical buckshot, one from another in a shotgun shell, said body having an arcuate casing wall-contacting face, a pair of buckshot contacting faces, converging together from the ends of said arcuate face, and a buckshot receiving concavity with its mouth defined by edges of said arcuate face and a pair of faces, and said body being provided with a plurality of spaced-apart substantially parallel indentations extending inwardly from said arcuate casing wall-contacting face.

7. As an article of manufacture a patterned body for separating substantially spherical buckshot, one from another in a shotgun shell, said body having an arcuate

5 casing wall-contacting face, a pair of buckshot contacting faces, converging together from the ends of said arcuate face, and a buckshot receiving concavity with its mouth defined by edges of said arcuate face and a pair of faces, and said body being provided with a plurality of spaced-apart indentations extending inwardly from said arcuate casing wall-contacting face to said pair of buckshot contacting faces.

8. As an article of manufacture a patterned body for separating substantially spherical buckshot, one from another in a shotgun shell, said body having an arcuate casing wall-contacting face, a pair of buckshot contacting faces, converging together from the ends of said arcuate face, and a buckshot receiving concavity with its mouth defined by edges of said arcuate face and a pair of faces, and said body being provided with a plurality of spaced-apart flutes extending inwardly from said arcuate casing wall-contacting face to said pair of buckshot contacting faces.
